CORNER SHELF

Martin M. Salen, 6303 Large St., Philadelphia, Pa.

Filed May 18, 1959, Ser. No. 55,962

Term of patent 14 years

(Cl. D33—18)

respectively disclosed in right angle relation, both sides being of similar design and configuration.

I claim:

I claim:
The ornamental design for a corner shelf, substantially as shown and described.
